CONTROL APPARATUS FOR PRINTING MACHINES

William C. Wiering, Woodhaven, and August Baumgartner, Hollis, N. Y., assignors to R. Hoe & Co., Inc., New York, N. Y., a corporation of New York

Application December 24, 1936, Serial No. 117,446

3 Claims. (Cl. 101—368)

This invention relates to printing machines of the rotary cylinder type and more particularly to an improvement in such machines generally, consisting in the provision of a guard for the plate cylinder adapted and arranged in respect thereto whereby the machine may be operated with greater efficiency and safety.

The invention is especially applicable to printing machines having plate cylinders upon which plates are removably mounted and which are provided with plate clamping mechanism of the type wherein a removable wrench or operating handle is used to actuate the same, and which is insertable into clamp actuating position substantially 10 radially with respect to the cylinder. Such a type of mechanism is shown in H. V. Ball Patent No. 2,066,192 granted December 29, 1936, and herein this invention is shown and described as being applied in cooperation and combination 15 therewith.

One of the objects of this invention is to provide in a printing machine a plate cylinder guard which is movable from one position, wherein it permits the operation of a plate clamping mechanism and prevents machine operation, to another wherein the machine is permitted to be operated.

Another object is to provide a guard of the above nature for the plate cylinder of a printing machine, which when moved from one position, will actuate a suitable machine control to prevent operation of the machine and when in another position will permit operation of the machine.

A further object is to provide a guard for the plate cylinder of a printing machine which is adapted to be moved by a plate should the same become detached from the machine, and by such movement stop the machine.

A still further object is to provide in a printing machine of the above type the combination of a swingable plate cylinder guard and an electrical switch adapted to be actuated by the guard when it is swung from its plate embracing position, to stop the machine and prevent its further operation under normal control, until the guard is again disposed in its normal operable position.

It is also an object of this invention to provide a plate cylinder guard and control for a printing machine, of generally improved construction, whereby the same will be simple, durable and inexpensive in construction, as well as convenient, practical, serviceable and efficient in its use.

With the foregoing and other objects in view,

which will appear as the description proceeds, the invention resides in the combination and arrangement of parts, and in the details of construction hereinafter described and claimed.

The preferred embodiment of the invention is 5 illustrated in the accompanying drawing, wherein:

Figure 1 is a diagrammatic side view of a portion of a printing machine showing the ends of a printing unit comprising two pairs of plate 10 and impression cylinders and to which the features of this invention are applied, for cooperation with the plate cylinders and shown in different operable positions on each; and

Figure 2 is a face view of one of the plate cylinders looking in the direction of the arrow 2 in Figure 1.

The printing machine, a portion of which is illustrated in Figure 1, includes two cooperating pairs of plate and impression cylinders 11—12 20 and 13—14 respectively with suitable ink applying rollers 15 in operable association with each plate cylinder. The cylinders and rollers are journaled in suitable opposing machine frames 16. A web 17 is threaded between the respective cylinders of each pair and runs from a guide roller 18 to the first pair 11 and 12 and from the second pair 13 and 14 into the remaining portions of the machine. As fully disclosed in the above referred to Patent No. 2,066,192, each plate cylinder has a plurality of plates 19 clamped upon the cylinder periphery by axially movable clamping members 21 moved into clamping position by a rockable member (not shown) which is adapted to be actuated by a manually operable wrench or tool 22 insertable into a socket in a swingable member 24 operably connected to the rockable clamp actuating member, substantially 25 radially in respect to the respective cylinder.

As shown diagrammatically in Figure 1, a motor 25 for driving the printing machine is connected to the line wires L1 and L2 by conductors 26 and 27, the conductor 27 being interrupted by a switch 28 operable by a solenoid 29 to close the circuit. The coil of the solenoid 29 is connected to the line wire L1 by a conductor 31 and through a conductor 32, a normally open switch 33 having an actuating lever 34, a conductor 35, a circuit switch 36, and a conductor 35' to the line wire L2. The switch 36 shows in elementary form, a means for stopping and starting the machine. Such means is usually located within easy reach of the machine operator. Herein the switch 33 is arranged to close the circuit between the conductors 32 and 35 when the lever 35

34 is depressed, and being adapted to maintain this circuit normally open when the lever is released.

Guards 37 and 37' are provided, which are hingedly mounted upon shafts 38 and 38' secured to and extending between the frames 16. The guards 37 and 37' are arranged to extend up and over the plate cylinders 13 and 11 respectively and are curved about the respective cylinders to embrace an exposed face portion thereof. The switch 33 is mounted upon one of the frames 16 in position to have its actuating lever 34 engaged by a portion of the guard 37 above the axis of the shaft 38 when the guard is moved into position adjacent the cylinder and depress the lever 34 to close the circuit as shown at the left in Figure 1 relative to the cylinder 11. This action will energize the solenoid 29 and close the motor control switch 28, whereby the motor 25 may be operated to drive the machine and rotate the cylinders 11, 12, 13 and 14. Swinging the guard 37 away from the cylinder, as shown at the right in Figure 1 relative to the cylinder 13, permits the actuating lever 34 to be released, whereby the circuit is opened and the solenoid 29 is deenergized and opens the switch 28 to prevent or interrupt the operation of the motor 25.

The guard 37 is arranged to cover the entire length of the plate cylinder at its exposed face portion and therefore the socket in which the wrench or clamp mechanism operating tool 22 is insertable, is covered when the guard is in operative position and prevents the tool 22 being used. Upon swinging the guard 37 to sufficiently uncover the socket for the insertion of the tool 22 to actuate the clamping mechanism, the switch 33 will be actuated to open the circuit as above described. This arrangement prevents the starting of the machine while a tool 22 is in position to actuate the clamps, as the guard 37 cannot be moved sufficiently to actuate the switch 33 until the tool 22 is removed from its socket. The guard 37 also acts as an automatic stop means for the machine, should a plate break and be thrown from the cylinder whereupon it would move the guard 37 away from the cylinder and release the actuating lever 34.

A similar switch 33' is shown in the drawing arranged in engagement with the guard 37', but the wiring of this switch has been omitted for the sake of clearness. It will be understood that this switch and (as in the case of a multi-unit printing machine), any additional switches employed will all be connected in series with the switch 33 and serve to interrupt the circuit through the solenoid 29 when any one of the guards is swung away from the cylinder.

Another advantage of the above described structure and arrangement resides in the switches 33 and 33' being exposed so as to permit manual operation when the guards 37 and 37' are swung to their down position, as shown in respect to guard 37 at the right hand side of Figure 1. This permits the operator to start the machine and run it momentarily with a guard down, to move the cylinder 13, a part of a revolution, and into position whereby a plate 19 may be conveniently applied thereto. For instance, after applying one plate 19 to the cylinder 13, the operator, due to the accessibility of the switch 33, when the guard 37 is down may depress its operating lever 34 and by simultaneously operating the starting switch 36 cause the cylinder 13 to rotate, while the lever 34 is depressed. This obviates the necessity for raising the guard every time it is de-

sired to move the printing cylinders slightly. The machine, however, cannot be operated normally without all of the guards 37 and 37' being in their cylinder guarding position.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What we claim is:

1. In a rotary printing machine having a plate cylinder, rotary inking mechanism cooperating with and having components engaging the plate cylinder, an impression cylinder operably engaging the plate cylinder, the plate cylinder, impression cylinder and inking mechanism being constructed and arranged to expose a plating area at the peripheral portion of the plate cylinder which is normally accessible for securing and removing plates from the cylinder and adjusting the plates thereon, a plurality of plates removably secured to the plate cylinder, a motor to rotate the plate cylinder; a control for said motor including a circuit interrupter having an actuating lever, an arcuate guard plate pivotally supported at one longitudinal edge to be swung over said cylinder to cylinder-covering position in substantially concentric relation thereto and movable about its pivotal support away from the cylinder to cylinder-exposing position, said guard plate being at least of sufficient length and area to substantially cover or guard the said plating area of the plate cylinder to thereby cover the plates on the plating area of the plate cylinder, said actuating lever being disposed in the path of the said guard plate to be engaged thereby to close the said circuit when the guard plate is in cylinder-covering position to close the said electric circuit to permit operation of the said motor, the actuating lever immediately moving to circuit-breaking position during the initial movement of the guard plate in its movement about its pivotal support away from the cylinder toward cylinder-exposing position, the guard plate being yieldably movable away from cylinder-covering position and when moved from cylinder-covering position disengaging the actuating lever and exposing it for convenient manual operation.

2. In a rotary printing machine having a plate cylinder, rotary inking mechanism cooperating with and having components engaging the plate cylinder, an impression cylinder operably engaging the plate cylinder, the plate cylinder, impression cylinder and inking mechanism being constructed and arranged to expose a plating area at the peripheral portion of the plate cylinder which is normally accessible for securing plates to and removing them from the cylinder and adjusting the plates thereon, a plurality of plates supported by the plate cylinder, plate clamping mechanism operably supported by the cylinder to secure the plates to the plate cylinder, a radially-extending socket pivotally secured to the cylinder and operably connected with the plate clamping mechanism to operate the plate clamping mechanism by the pivotal movement of the said socket, the socket receiving therein a removable radially-extending operating tool, a motor to rotate the plate cylinder; a control for said motor including a circuit interrupter having an actuat-

ing lever, an arcuate guard plate pivotally supported at one longitudinal edge to be swung over said cylinder to cylinder-covering position in substantially concentric relation thereto and movable about its pivotal support away from the cylinder to cylinder-exposing position, said guard plate being at least of sufficient length and area to substantially cover or guard the said plating area of the plate cylinder to thereby cover the plates on the plating area of the plate cylinder, said actuating lever being disposed in the path of the said guard plate to be engaged thereby to close the said circuit when the guard plate is in cylinder-covering position to close the said electric circuit to permit operation of the said motor, the actuating lever immediately moving to circuit-breaking position during initial movement of the guard plate in its movement about its pivotal support away from the cylinder towards cylinder-exposing position, the guard plate being yieldably movable away from cylinder-covering position and then moved away from cylinder-covering position disengaging the actuating lever and exposing it for convenient manual operation, the presence of the said radially-extending operating tool in its receiving socket preventing the movement of the guard plate to cylinder-covering position.

3. In a rotary printing machine having a plate cylinder, rotary inking mechanism cooperating with and having components engaging the plate cylinder, an impression cylinder operably engaging the plate cylinder, the plate cylinder, impression cylinder and inking mechanism being constructed and arranged to expose a plating area at the peripheral portion of the plate cylinder which is normally accessible for securing plates to and removing them from the cylinder and adjusting the plates thereon, a plurality of plates supported by the plate cylinder, plate-clamping mechanism operably supported by the cylinder to secure the plates to the plate cylinder, a radially-extending socket pivotally secured to the cylinder and operably connected with the plate-clamping mechanism to operate the plate-clamping mechanism by the pivotal movement of the said socket, the socket receiving therein a removable radially-extending operating tool, a motor to rotate the plate cylinder; a control for said motor including a circuit interrupter having an actuating lever, an arcuate guard plate pivotally supported at one longitudinal edge to be swung over said cylinder to cylinder-covering position in substantially concentric relation thereto and movable about its pivotal support away from the cylinder to cylinder-exposing position, said guard plate being at least of sufficient length and area to substantially cover or guard the said plating area of the plate cylinder to thereby cover the plates on the plating area of the plate cylinder, said actuating lever being disposed in the path of the said guard plate to be engaged thereby to close the said circuit when the guard plate is in cylinder-covering position to close the said electric circuit to permit operation of the said motor, the actuating lever immediately moving to circuit-breaking position during initial movement of the guard plate in its movement about its pivotal support away from the cylinder towards cylinder-exposing position, the guard plate being yieldably movable away from cylinder-covering position responsive to the impact of a printing plate or portion thereof and when moved from cylinder-covering position disengaging the actuating lever to stop the press, the presence of the said radially-extending operating tool in its receiving socket preventing the movement of the guard plate to cylinder-covering position.

WILLIAM C. WIEKING.
AUGUST BAUMGARTNER.
